UNITED STATES PATENT OFFICE.

GILES VALINTINE SULLIVAN, OF SAN FRANCISCO, CALIFORNIA, ASSIGNOR TO BETHLEHEM SHIPBUILDING CORPORATION, LTD., OF BETHLEHEM, PENNSYLVANIA, A CORPORATION OF DELAWARE.

MACHINE FOR SETTING TURBINE-BLADES.

1,319,732.

Specification of Letters Patent.

Patented Oct. 28, 1919.

Application filed December 4, 1918. Serial No. 265,282.

To all whom it may concern:

Be it known that I, GILES VALINTINE SULLIVAN, a citizen of the United States, residing in the city and county of San Francisco, State of California, have invented a new and useful Machine for Setting Turbine-Blades, of which the following is a specification.

My invention consists of a novel machine 10 for setting turbine blades with respect to a turbine disk.

It further consists of a novel construction of a machine for setting turbine blades on a turbine disk, which can be adapted to various 15 diameters of disks, wherein I provide novel means for rotatably supporting the turbine disk, in conjunction with means for rotating said disk and its adjuncts in a desired direction during the setting of the 20 blades, means being provided for reversing the direction of rotation of the disk so as to set the blades on an opposite portion thereof, whereby time and labor are reduced to a minimum and the blades are all evenly and 25 accurately set and assembled in a much more expeditious and effective manner than is possible where the blades have been inserted and calked in place by hand.

To the above ends, my invention consists 30 of a novel construction and arrangement of gearing with respect to an electric or other prime motor, whereby the shaft or head carrying the turbine disk or on which said disk is centered can be revolved in either direction or reversed at will, thereby permitting a limited rotary movement of the turbine disk and the turbine blade thereon until the latter contacts with a suitable abutment or jaw tool which arrests the movement 35 of said blade and effects the setting of the blades in a rapid and effective manner.

For the purpose of illustrating my invention, I have shown in the accompanying drawings one form thereof which is at present preferred by me, since the same will be found in practice to give satisfactory and reliable results, although it is to be understood that the various instrumentalities of which my invention consists can be variously 45 arranged and organized and that my invention is not limited to the precise arrangement and organization of these instrumen-

talities as herein shown and described, except as required by the scope of the appended claims.

55

Figure 1 represents a front elevation of a machine for setting turbine blades embodying my invention, showing also an end elevation of a turbine disk and blades thereon.

Fig. 2 represents an end view or right 60 hand elevation of Fig. 1.

Fig. 3 represents a section on line 3—3 of Fig. 2 through the outer periphery of the turbine disk, showing a plan view of a portion of a turbine blade.

65

Fig. 4 represents a perspective detail of the jaw tool, tool post and their adjuncts.

70

Fig. 5 represents a perspective view showing the manner of initially inserting a turbine blade in position.

75

Similar numerals of reference indicate corresponding parts.

Referring to the drawings,

1 designates the housing or frame-work of my novel machine for setting turbine 75 blades, which in the present instance is shown as being built up out of the head of a Gisholt lathe changed to suit the conditions and requirements hereinafter referred to.

2 designates the shaft of the lathe head 3, 80 which is provided with a chuck 4, which may be of any suitable or conventional type, as will be understood from Fig. 2, said shaft 2 being mounted in suitable bearings on said frame-work or housing.

5 designates an electric or other prime motor, which is reversible, whereby the shaft 6, which is mounted in suitable bearings, may be rotated at will in either direction, said shaft carrying the worm 7, which is in mesh 90 with the worm gear 8, which I have shown as being fitted on or attached to one of the stepped cones 9, it being understood that said worm gear 8, cone 9 and shaft 2 rotate in unison, 10 designating the smaller 95 member of the cone surface of the lathe converted into my invention.

I have deemed it unnecessary to show or describe the manner of reversing the motor, as any suitable type of reversible motor 100 or reversing mechanism therefor may be employed.

11 designates a pinion mounted on the shaft 2, so as to rotate in unison therewith,

said pinion 11 meshing with the gear 12, which is mounted on the shaft 13, which revolves in suitable bearings 14.

15 designates a pinion mounted on the 5 shaft 13 and in mesh with the gear 16, which is mounted on the shaft 2. 17 designates a standard having on its upper portion 18 a slotted jaw tool or abutment 19, whose construction will be understood from the 10 perspective view in Fig. 4, said jaw tool 19 being clamped in position by any suitable means, as will be understood from said figure, and being capable of being moved toward or away from the turbine disk, so as 15 to accommodate disks of varying diameters.

20 designates the turbine disk to be bladed, which comprises a suitable web or body portion having a peripheral head or rim 21, whose contour in cross-section will 25 be best understood from Figs. 3 and 5, said head or rim being shown as a polygonal enlargement extending peripherally around the turbine disk body, and having as at the points 22 in its circumference, radial cut 30 away portions in the periphery of the head 21, which are cut down flush with each side of said web or body portion, as best seen in Fig. 5.

23 designates the turbine blade, which 35 may be of the usual form and character, each being provided with a base portion 24, as seen in Figs. 3 and 5, and each of said base portions having a slot therein formed by the walls 25 and 26, which conform to 40 the contour of the peripheral rim or head 21, the rear wall of said slot being open, as indicated at 27.

The method of setting the turbine blades on a turbine disk is as follows:

45 The turbine disk having been suitably centered in the jaws 28^x of the chuck 4, seen in Fig. 2, the turbine blades are slipped on the turbine disk through the slots 22 seen in Figs. 2 and 5, which slots at the time of the introduction of a blade 23 may 50 be located for instance either above the abutment or jaw tool 19 as at about the point A—A above the jaw tool or below said jaw tool, as at about the point B—B. A light tap of a hammer starts the blade on the rim 21 of the disk, then the motor 5 is started, and by the revolution of the disk 20, the blade is brought into contact with the jaw tool on the tool post. When the 55 parts are in the position seen in Fig. 2, assuming that a turbine blade has been placed in position in the slot 22, when it was above the jaw tool 19, it will be understood, assuming the rotation of the turbine blade to be 60 in the direction of the arrow *a*, that the blade 23^a has come to rest against the top of the abutment 19 and that the rotation of the turbine blade will continue until said turbine blade 23^a seen immediately above 65 the jaw tool 19 is contiguous to the wall 29

of the turbine blade 23^b seen at the right of Fig. 2. The motor is stopped at this point and its direction of rotation is now reversed, whereupon the turbine blade 23^c seen at the lower left-hand portion of Fig. 2, having been placed in the position seen, will abut against the bottom of the jaw tool 19 and the rotation of the turbine disk 20 in a direction opposite to the arrow *a*, will bring the wall 30 of said turbine blade 23^c 75 seen at the left of Fig. 2 below the jaw tool against the wall 31 of the turbine blade 23^d seen at the right of Fig. 2.

The operation is thus repeated, the direction of the rotation of the motor being alternately reversed until the disk has been 80 completely bladed.

It will be seen from the foregoing that after the application of the first blade and the securing of it in place upon the rim of the turbine disk, the operation of applying additional blades is continuous, until the total which the disk will carry has been applied. The entire operation is one of the application of blades and the alternate 90 reversal of the turbine disk, the reversal becoming gradually less in circumferential extent in both directions, until the disk is bladed, the blades contacting with each other in the sequence of their application. 95

The first blade applied to the rim can be secured in position in any approved or desired manner, and the last blade occupying the space in proximity to the recesses 22 can also be secured in position and said recesses plugged up, if desired, in any suitable manner. 100

It will be understood that the contour of the slot 19^x in the jaw tool 19 can be varied, if desired, and said jaw tool can be moved 105 toward or away from the chuck 4 by loosening the bolts 28 and the clamping plate 29, thereby permitting the shifting of said jaw tool, or, if desired, the tool post 17 and its adjuncts can be shifted to accommodate 110 turbine disks of different diameters. 110

By my novel machine for setting turbine blades, it will be apparent that a blade is set during each partial rotation of the turbine disk in either direction, so that time and labor are economized and all the turbine blades are evenly set with respect to the turbine disk, so that no subsequent rectifying of the blades is necessary, which rectifying is necessary where the turbine blades have been inserted and calked by hand. 115

It will be understood that all the turbine blades as 23, 23^a, 23^b, 23^c and 23^d, are identical, and that I have used the different designations therefor, for the purpose of clearly 120 explaining the operations referred to.

While I have shown but one type of turbine disk having a rim of the configuration and contour of the slot in the coacting turbine blades seen in Figs. 3 and 5, it will be 125 130

evident that the broad principle of my invention is equally applicable to turbine disks having rims of different contour and turbine blades differently slotted from the 5 construction shown.

It will now be apparent that I have devised a novel and useful construction of a machine for setting turbine blades which embodies the features of advantage enumerated 10 as desirable in the statement of the invention and the above description, and while I have, in the present instance shown and described a preferred embodiment thereof which will give in practice satisfactory and reliable results, it is to be understood that this embodiment is susceptible of modification in various particulars without departing from the scope of the appended claims.

Having thus described my invention, what I claim as new and desire to secure by Letters Patent, is:—

1. In a machine for setting turbine blades on a turbine disk, means to rotate said disk, 25 and means to engage a turbine blade assembled on said disk and to effect the setting of such blade in proper position on said disk during the rotation of the latter.

2. In a machine for setting turbine blades 30 on a turbine disk, means to rotate said disk, and an abutment adapted to engage a turbine blade assembled on said disk and to effect the setting of such blade in proper position on said disk during the rotation of the latter, in combination with means for reversing the direction of rotation of said disk.

3. In a machine for setting turbine blades 40 on a turbine disk, a support for a turbine disk, means for rotating said support and disk in either direction, and a slotted abutment adapted to engage a turbine blade and arrest its movement during the limited continued rotation of said support and disk.

4. In a machine for setting turbine blades 45 on a turbine disk, a support for a turbine disk, means for rotating said support and disk in either direction, and a slotted abutment adapted to engage a turbine blade and arrest its movement during the limited continued rotation of said support and disk, in

combination with means for adjusting the position of said abutment with respect to said turbine disk support.

5. In a machine for setting turbine blades 55 on a turbine disk, means for supporting and rotating a turbine disk, means for reversing the direction of rotation of said disk, and means for arresting the movement of a turbine blade with respect to said disk during 60 the rotation of the latter in either direction.

6. In a machine for setting turbine blades on a turbine disk, a motor, a motor shaft, a worm on said motor shaft, a shaft located above said motor shaft, a worm carried 65 thereby, a pinion on said latter shaft, a gear in mesh with said pinion, an upper shaft on which said gear is mounted, bearings for said upper shaft, a pinion on said latter shaft, a gear on the shaft carrying 70 said worm, a chuck for a turbine disk on said worm shaft, and an abutment adapted to be adjusted with respect to said chuck for arresting the movement of a turbine blade with respect to said disk. 75

7. In a machine for setting turbine blades on a turbine disk, a motor, a motor shaft, a worm on said motor shaft, a shaft located above said motor shaft, a worm carried 80 thereby, a pinion on said latter shaft, a gear in mesh with said pinion, an upper shaft on which said gear is mounted, bearings for said upper shaft, a pinion on said latter shaft, a gear on the shaft carrying said 85 worm, a chuck for a turbine disk on said worm shaft, and an abutment adapted to be adjusted with respect to said chuck for arresting the movement of a turbine blade with respect to said disk, said motor being capable of rotation in either direction. 90

8. In a machine for setting turbine blades, means for centering a turbine disk, means for rotating said disk in opposite directions, and an abutment or jaw tool having a projecting member located in proximity to the 95 rim of said turbine disk and adapted to arrest the movement of the turbine blade with respect to said turbine disk.
